Primary Examiner — Selina Sikder(74) *Attorney, Agent, or Firm* — Sheridan Ross P.C.(57) **CLAIM**

The ornamental design for an automobile remote controller, as shown and described.

DESCRIPTION

FIG. 1 is a first perspective view of the automobile remote controller;

FIG. 2 is a second perspective view of the automobile remote controller;

FIG. 3 is a third perspective view of the automobile remote controller;

FIG. 4 is a front view of the automobile remote controller;

FIG. 5 is a rear view of the automobile remote controller;

FIG. 6 is a left side view of the automobile remote controller; and,

FIG. 7 is a right side view of the automobile remote controller.

1 Claim, 4 Drawing Sheets(56)
